UNITED STATES PATENT OFFICE.

GEORGE GORTON, OF RACINE, WISCONSIN, ASSIGNOR TO ROBINSON & ROBINSON, OF RACINE, WISCONSIN, A COPARTNERSHIP CONSISTING OF RICHARD T. ROBINSON AND RICHARD T. ROBINSON, JR.

MOLD FOR ROTARY VALVES.

1,137,203.

Specification of Letters Patent.

Patented Apr. 27, 1915.

Application filed February 6, 1915. Serial No. 6,445.

To all whom it may concern:

Be it known that I, GEORGE GORTON, a resident of Racine, in the county of Racine and State of Wisconsin, have invented certain new and useful Improvements in Molds for Rotary Valves, of which the following is a full, clear, and exact description.

The invention relates to molds for rotary valves.

10 In water-cooled valves for multi-cylinder explosive engines, it has been found desirable to employ a hollow valve with a water passage extending longitudinally therethrough and with integral portions in 15 which through-ports are formed and with an integral gear for rotating the valve, and it has also been found to be important to provide a hard metal peripheral wearing-surface and an interior of comparatively 20 soft metal to withstand breaking stresses to which the valve is subjected in practice.

The object of the present invention is to provide an improved mold for casting valves of this character.

25 A further object is to provide an improved mold for a rotary valve, which is efficient in operation and wherefrom uniformity in casting will result.

The invention consists in the several novel 30 features hereinafter set forth and more particularly defined by claims at the conclusion hereof.

In the drawings: Figure 1 is a central vertical section of a mold embodying the 35 invention and showing the manner of casting the valve. Fig. 2 is a detail perspective of the central core for forming the longitudinal opening in the valve. Fig. 3 is a detail view, partly in elevation and partly in 40 section, of the valve casting. Fig. 4 is a plan of the pouring-core. Fig. 5 is a plan of the mold, the pouring core being omitted. Fig. 6 is a section taken on line 6-6 of Fig. 45 Fig. 7 is a detail perspective of one of the sectional chill rings and the core adapted to be held therein for forming a through-port in the valve, the parts being shown in separated relation. Fig. 8 is a detail perspective of the ring for forming the gear 50 on the valve.

The improved mold is adapted to form a hollow or cylindrical valve *e* which is adapted to rotate in a suitable valve-seat. This valve is formed with relatively offset

through-ports *e'* (one for each cylinder) to 55 successively serve as exhaust and intake ports. This valve is hollow or tubular to provide a passage or chamber *e*, extending from end to end thereof, to permit cooling water to flow longitudinally through the 60 valve. At each end, the valve is formed with an integral cross-rib *s*, which serves as an abutment for means (not shown) for holding the valve longitudinally positioned in its seat. A sprocket or gear-wheel *l*, whereby the valve will be driven, is integrally formed on the exposed portion of the rotary valve. In practice, it has been found to be of importance to provide a hard wearing surface on the periphery of the valve and 70 to form the remaining portions of the valve of softer metal to render the valve less breakable and one of the objects of the invention is to provide a mold which will produce this result.

75 The improved mold comprises a base-plate 20 upon which a sleeve 21 is removably mounted, being positioned on the base-plate by a raised portion 22 of the plate, which fits into the lower end of the sleeve. Split 80 chill-rings 24 are placed in superposed relation in the sleeve 21, and dry-sand cores 25 for forming the valve-ports *e'*, are placed and held in these rings. Each chill-ring is formed of semi-cylindrical sections, the 85 abutting edges of which have recesses 26 for receiving the ends of cores 25, so that each core will be held in the contiguous recesses of the sections of a ring.

A key rib 27 is formed on the inside of 90 sleeve 21 and grooves 27' on the chill-rings serve to position the rings so that the ports will be formed at the proper relative angles to become successively operative in the rotation of the valve. Rib 27 also extends into a 95 groove on the periphery of extension 22 of plate 20, so that it will be locked against rotation relative to said plate, and so that the chill-rings and port-cores will always be in same relative position to base-plate and 100 sleeve. A one-piece chill-ring 28 is placed in the sleeve 21 on top of the uppermost chill-ring 24 and this ring 28 is provided with internal teeth for forming the gear *l* on the valve. A chill-ring 29 is placed on 105 top of ring 28 to form one of the end portions of the valve. A cylindrical dry-sand core 30 is placed within the chill-rings to

leave spaces between the inner periphery of the chill-rings and the outer periphery of the core to form the cylindrical wall of the valve. This dry-sand core 30 is provided with cross-openings 38 around cores 25 to form the surrounding walls of the ports e' in the valve, and with cavities 30' for forming the end lugs s in the valve. A cavity 31 is formed in the base 20 to receive a reduced lower end 30^a of the core 30 and a vent 32 is formed in said core in the base 20. This end 30^a and cavity 31 are irregularly formed so that the core can enter the cavity only when the core is in proper relative position to the cores 25. By providing this interfitting connection, which positions the core 30 on the plate 20, the interlock between sleeve 21 and plate 20 and the interlock between the sleeve and the chill-rings, which hold port-cores 25, the several parts of the mold will always be correctly assembled, so that the ports e' will be formed in correct relative position. A pouring core 33 is placed on the top of the chill-ring 29 and is held in an enlarged end or recess 34 formed in the top of sleeve 21. Pouring-gates 35, leading to the casting spaces, are formed in said pouring-core. A vent 36 is formed in the upper end of the dry-sand core 30 and a cross-vent 37 is formed in the pouring core 33.

In assembling the mold, the dry-sand core 30 is first placed on the base-plate 20. A core 25 is then passed through the lowermost opening 38 in the core 30 and is held therein by placing the sections of the lowermost chill-ring 24 in position around the core 30. The remaining cores 25 and chill-rings 24 are successively placed in superposed relation around the core 30 in the same manner. Next, the chill-rings 28 and 29 are placed in position. Sleeve 21 is then dropped over the vertical series of chill-rings and into position on plate 20, so that all of the chill-rings will be held in superposed relation and in proper relative position to form the valve and through-ports therein. This sleeve can be lowered into position only when the grooves 27' are alined with the groove for rib 27 in the plate 20, and as a result all the port-cores will be correctly positioned in the central core 30 to form the walls around the ports and to form them in proper correlative position. The pouring gate 33 is then placed in position, whereupon the entire mold will be assembled for a casting operation.

When the metal is poured into the pouring-gates 35, it will flow into the spaces corresponding to the shape of the valve and integrally form all portions of said valve. The metal forming the outer or peripheral portion of the cylindrical wall of the valve will be chilled as it comes in contact with the chill-rings for a distance, corresponding in practice to about $\frac{1}{8}$ th of an inch. In-

wardly of the chilled portion, the metal will anneal, because the dry-sand cores will not have any chilling effect upon the metal. As a result of molding the valve in this manner, its periphery will be harder or denser than the inner portion of the metal wall of the sleeve. This will provide the desired wear-surface on the outer periphery and the annealed inner portion will be less brittle to resist breakage, resulting from a shock or blow. The gear 1 will also be chilled so that it will not readily wear.

When the casting has been formed in the mold, it will be removed therefrom in the following manner; the pouring gate 33 will be removed, sleeve 21 will then be lifted away from the chill-rings and the latter being formed in sections can be removed from the casting.

The invention thus exemplifies a mold which is particularly adapted for forming a hollow rotary valve with through-ports therein and by which the valve will be formed with inner and outer metal portions of different densities.

The invention is not to be understood as restricted to the details set forth, since these may be modified within the scope of the appended claims, without departing from the spirit and scope of the invention.

Having thus described the invention, what I claim as new and desire to secure by Letters Patent; is:

1. In a mold for engine valves, the combination of a central core for forming a longitudinal duct in the valve, cores for forming ports through the valve, sectional-rings around the central core, provided with means for holding the port-cores, and means for holding said rings together.

2. In a mold for engine valves, the combination of a central core for forming a longitudinal duct in the valve, cores for forming ports through the valve, sectional chill-rings around the central core and provided with means for holding the port-cores, and means for holding said rings together.

3. In a mold for engine valves, the combination of a central core for forming a longitudinal duct in the valve, cores for forming ports in the valve, sectional rings around the central core provided with recesses in their contiguous ends for holding the port cores, and means for holding said rings together.

4. In a mold for engine valves, the combination of a central core for forming a longitudinal duct in the valve, cores for forming ports through the valve, sectional chill-rings around the central core and provided with means for holding the port-cores and a sleeve fitting around the sections of the rings serving to hold them together.

5. In a mold for engine valves, the combination of a central core for forming a longitudinal duct in the valve, cores for forming

ports through the valve, sectional-rings around the central core and provided with means for holding the port-cores and a sleeve fitting around the sectional rings to hold them together.

5 6. In a mold for engine valves, the combination of a central core for forming a longitudinal duct in the valve, cores for forming ports in the valve, sectional-rings around the central core, provided with recesses in their contiguous ends for holding the port-cores, and a sleeve fitting around the sectional rings and serving to hold them together.

10 7. In a mold for engine valves, the combination of a central core for forming a longitudinal duct in the valve, cores for forming ports through the valve, sectional-rings around the central core and provided with means for holding the port-cores, a base plate, and a sleeve on the base plate and by which the sections of the rings are held together.

15 8. In a mold for engine valves, the combination of a central core for forming a longitudinal duct in the valve, cores for forming ports in the valve, chill-rings formed of separable sections around the central core and provided with means for holding the port-cores, a base and a sleeve on the base and by which the sections of the rings are held together.

20 9. In a mold for engine valves, the combination of a central core for forming a longitudinal duct in the valve, cores for forming ports in the valve, superposed rings formed of separable sections around the central core and provided with means for holding the port-cores, a base, and a sleeve on the base by which the rings are held together, the lower end of the central core and the plate being provided with a vent.

25 10. In a mold for engine valves, the combination of a central core for forming a longitudinal duct in the valve, cores for forming ports through the valve, sectional rings around the central core and provided with means for holding the port-cores, a sleeve fitting around the sectional rings, and an interfitting connection between the rings and the sleeve for holding the rings against rotation and relatively positioning the rings and port-cores therein.

30 11. In a mold for engine valves, the combination of a central core for forming a longitudinal duct in the valve, cores for forming ports through the valve, sectional rings around the central core and provided with means for holding the port-cores, a sleeve fitting around the sectional rings and an interfitting rib and groove connection between the rings and the sleeve for holding the rings against rotation and relatively positioning the rings and port-cores therein.

35 12. In a mold for engine valves, the com-

bination of a central core for forming a longitudinal duct in the valve, cores for forming ports through the valve superimposed rings formed of separable sections, around the central core and provided with means for holding the port-cores, a sleeve fitting around the split ring, a one-piece ring above the sectional-rings, and an interfitting connection between said rings and the sleeve for holding the rings against rotation and relatively positioning the rings and port-cores therein.

40 13. In a mold for engine valves, the combination of a central core for forming a longitudinal opening in the valve, cores for forming ports in the valve, superimposed rings around the central core and provided with means for holding the port-cores, a ring having means for forming teeth on the periphery of the valve, and means for holding said rings together.

45 14. In a mold for engine-valves, the combination of a central core for forming a longitudinal duct in the valve, cores for forming ports through the valve, superimposed rings formed of separable sections, around the central core and provided with means for holding the port-cores, a ring having means for forming teeth on the periphery of the valve, and a sleeve around said rings.

50 15. In a mold for engine valves, the combination of a central core for forming a longitudinal duct in the valve, cores for forming ports through the valve, superimposed rings formed of separable sections, around the central core and provided with means for holding the port-cores, a one-piece ring having means for forming teeth on the periphery of the valve, and means for holding said rings together.

55 16. In a mold for engine valves, the combination of a central core for forming a longitudinal duct in the valve, cores for forming ports in the valve, superimposed rings around the central core and provided with means for holding the port-cores, a base-plate, an interfitting connection between the base-plate and the central-core whereby said core will be held against rotation relatively to the plate, and a sleeve around the rings.

60 17. In a mold for engine-valves, the combination of a central core for forming a longitudinal duct in the valve, cores for forming ports through the valve, superimposed rings formed of separable sections, around the central core and provided with means for holding the port-cores, a base-plate, an interfitting connection between the base-plate and the central core whereby said core will be held against rotation relatively to the plate, and a sleeve around the rings.

65 18. In a mold for engine valves, the combination of a central core for forming a longitudinal duct in the valve, cores for

5 forming ports through the valve, superimposed rings around the central core, provided with means for holding the port-cores, a base-plate, an interfitting connection between the base-plate and the central core whereby said core will be held against rotation relatively to the plate, a sleeve around the split rings, and an interfitting connection between the plate and the sleeve
10 for relatively positioning the plate and sleeve.

15 19. In a mold for engine valves, the combination of a central core for forming a longitudinal duct in the valve, cores for forming ports through the valve, superimposed rings around the central core and provided with means for holding the port-cores, a base-plate, an interfitting connection between the base-plate and the central core whereby said core will be held against rotation relatively to the plate, a sleeve around the rings, and an interfitting connection between the rings and the sleeve for relatively positioning them with respect to the central core.

20 25 20. In a mold for engine valves, the combination of a central core for forming a longitudinal duct in the valve, cores for forming ports in the valve, superimposed rings around the central core and provided with means for holding the port-cores, a base-plate, an interfitting connection between the base-plate and the central core whereby said core will be held against rotation relatively to the plate, a sleeve around the split rings, and interfitting connections between the rings and the sleeve and said

plate for relatively positioning them with respect to the central core.

21. In a mold for engine valves, the combination of a central core for forming a longitudinal duct in the valve, cores for forming ports through the valve, superimposed rings around the central core, provided with means for holding the port-cores, a sleeve fitting around and holding the rings together, and a pouring-core held in the upper end of said sleeve.

22. In a mold for engine valves, the combination of a central core, for forming a longitudinal opening in the valve, cores for forming ports in the valve, sectional rings around the central core and provided with means for holding the port-cores, a sleeve fitting around the split rings, serving to hold them together, the sleeve being formed with an enlarged recess at its upper end and a pouring core held in said recess.

23. In a mold for engine valves, the combination of a central core for forming a longitudinal duct in the valve, cores for forming ports through the valve, superimposed rings around the central core and provided with means for holding the port-cores, a sleeve fitting around the split rings, serving to hold them together, and a pouring core held in the upper end of said sleeve, and provided with a vent for the escape of gases from the casting space.

GEORGE GORTON.
